UNITED STATES PATENT OFFICE

HARRY E. MORTON, OF HYDE PARK, MASSACHUSETTS

TOY ELECTRIC LOCOMOTIVE

Application filed December 17, 1927. Serial No. 240,915.

The present invention relates to toy electric locomotives and more particularly to a system for operating the headlamps thereof.

Heretofore it has been the practice to operate the headlamps of such a locomotive by the power current, that is, the current employed for propelling the locomotive, which current is controlled by the operator at some distant point. With this arrangement, the headlamp of the locomotive will be lighted only when the locomotive is in motion, the shutting off of the power circuit necessarily cutting off current from the headlamp.

Where, in the case of reversible locomotives, a headlamp is provided at each end, the desired headlamp in accordance with the intended direction of movement of the locomotive is thrown into the circuit by means of a switch either manually actuated by the operator or controlled by some abutment placed adjacent to the track which is engaged by switch actuating mechanism carried by the locomotive. With these arrangements, neither of which permits selective remote control by the operator of the headlamps, the current for whichever headlamp is in circuit is still derived from the power circuit so that when the power circuit is cut off to bring the locomotive to a standstill and to keep it at rest, neither headlamp can be in operation.

It is one of the objects of the present invention to provide a system of operating the headlamp of an electric toy locomotive whereby the lamp may be in operation irrespective of whether the locomotive is in motion or is stationary.

A further object of the present invention is to provide for the controlling of the headlamps of a reversible locomotive so that the proper headlamp for the intended direction of motion may be brought in the lighting circuit at the will of the operator and from a remote point, and also independent of the position of the locomotive.

Still another object of the present invention is to provide a remote control by the operator for a toy electric locomotive whereby either headlamp may be brought into operation while the locomotive is stationary and

the proper headlamp will be lighted according to the direction of motion of the locomotive when the latter is moving.

A still further object of the present invention is to provide a headlamp system for electric toy locomotives in which means are employed for automatically regulating the current through the headlamp so that wide fluctuations of brilliancy in the lamp will be avoided.

With these objects in view, the present invention consists in the devices and methods hereinafter described and illustrated. For convenience, the preferred forms of these devices and methods are described and illustrated in connection with the toy locomotive reversing mechanism covered by my Letters Patent No. 1,569,233, issued January 12, 1926.

In the accompanying drawings, Fig. 1 shows diagrammatically a motor car or locomotive, its headlamps, and the control devices with associated wiring and circuit connections; and Fig. 2 is an enlarged view of the movable contact block of the polarized switch carried by the locomotive and which in itself carries the movable contact elements which effect, in association with other fixed contacts, reversal of the motor and a change-over of the headlamps. A complete description of the motor reversing and control mechanism and circuits will be found in my Letters Patent No. 1,569,233 above referred to.

Briefly, however, in the construction shown in the drawings, the locomotive, indicated by wheels 8 and axles 10, is provided with a series motor 12 which has in the power circuit, in shunt with the motor circuit, a polarized switch 14 for reversing the armature leads of the motor. Besides the alternating current supply 51 for driving the motor there is a direct current supply from a small battery 67 for actuating the polarized reversing switch through the power circuit connections. A combined reversing switch 71 for the direct current and rheostat 57 for the alternating current is also provided, together with a supplementary switch 55 to 100

adapt the apparatus for use with either alternating or direct current.

Referring now to the drawings in detail and to those portions of the illustrations which concern the headlamps and their control, 97 and 98 are the headlamps at either end of the locomotive. One side of each headlamp is grounded to the frame of the locomotive as shown at 99 and 100. The other side of lamp 97 is connected through lead 101 to the fixed contact 102. The other side of the headlamp 98 is connected through lead 104 to fixed contact 106. Fixed contact 108 is connected through lead 109, ballast lamp 110, lead 112, and lead 32 to the third rail contact shoe 16 of the locomotive. The movable contact wiper 114 carried by the block 34 is sufficiently long to bridge the distance between two of the fixed contacts 102, 106 and 108.

As described in my Letters Patent No. 1,569,233, the control circuit for operating the motor reversing switch 14 includes a direct current source 67 connected by leads 68 and 70 to a control reversing switch 71 whereby the controlling direct current may be sent through the reversing switch 14 in either direction, as desired. This control switch 71 comprises five stationary contacts 72 and two movable bridge contacts 74 which latter are mounted on a swinging contact block 76. As shown in the drawing, the lead 68 is connected to the central stationary contact and the lead 70 is connected to both of the outer stationary contacts. One of the remaining contacts connects by a wire 80 to the lead 52 and the other by a wire 82 through contacts 84 and 86 of the switch 55 to a wire 88 leading to a pair of stationary contacts 90 and 92 which are arranged adjacent to the open ends of the rheostat coils for engagement with the arm 66. The engagement of the arm 66 with either of the contacts 90 or 92 closes the circuit from the direct current source to the rails 4 and 6 and causes energization of the polarized switch 14.

In order to reverse the direction of the direct current in the leads 80 and 82, the contact block 76 is pivoted at 94 and is provided with two pins 96 adapted for selective engagement with the end of the contact arm 66. With the parts in the position shown in full lines in the drawings, if the contact arm is moved in a clockwise direction, the end of the arm will engage with a right hand pin 96 and cause rotation of the contact block and the consequent reversal of the direct current connections. Continued movement of the arm 66 will close the direct current controlling circuit and thereafter the power circuit.

The direct current source 67 is of sufficiently low voltage not to cause operation of the locomotive driving motor when the said

direct current control voltage is impressed upon the rails. The headlamps 97 and 98 have a low voltage rating, preferably somewhat less than the voltage of the direct current source, so that when this control voltage is impressed across the series circuit consisting of one headlamp and the ballast lamp through the associated circuit, the voltage drop through the ballast lamp is of such value as to limit the drop across the headlamp to approximately its rated voltage. The ballast lamp 110 itself having a specially designed filament, possesses a temperature-resistance characteristic of such a nature that for a reasonable range of impressed voltage, the current through the same is practically constant. In this fashion, the ballast lamp acts as a constant current regulator and serves to maintain an even brilliancy of the headlamp while the locomotive is at rest and during its entire range of speed. Since the regulation provided by the ballast lamp is dependent upon changes in the resistance of the filament due to changes in temperature thereof, and since the impressed voltage variations which will occur in the case at hand will take place rapidly, it is essential that the regulating device take the form of such a ballast lamp. Heating and cooling of the filament thereof will take place rapidly and with inconsequential lag behind the changes in power producing the same. Again, since a range of several volts must be compensated for, it is necessary that the change in resistance caused by heating shall be relatively quite great. This can only be obtained by very large changes in temperature and the use of a filament material possessing a high positive temperature-resistance coefficient such as tungsten. The ballast lamp is to be enclosed within the body of the locomotive in the most convenient location, such location being one which will allow of access to the lamp for the purpose of renewal.

The operation of the system is described as follows:—Only that part of the sequence of operations having to do with the reversal of the motor which is common to the selective functioning of the headlamps will be described herein. A complete description of said mechanism of motor reversal will be found in my Letters Patent 1,569,233.

Assuming that the switch 55 is set for the operation of the locomotive on alternating current and the control on direct current, and that the switch arm 66 of rheostat 57 is set at the neutral position, in other words, touching neither contact 90 nor 92, neither direct nor alternating voltage is impressed across the rails. The control reversing switch 71 will then stand in either of its two positions.

The switch arm 66 is now moved onto either contact 90 or 92 according to the in-

tended direction of motion of the locomotive. Immediately this contact is established, the proper headlamp 97 or 98 will be lighted. If the switch arm 66 was moved in the direction such that further movement will cause the locomotive to move in the direction in which it was last moving, then the forward headlamp relative to this direction of motion will light. If the switch arm 66 was moved from neutral in the opposite direction, it will engage one of the pins 96 on the control reversing switch 71 operating to reverse the succeeding flow of direct current to the changeover switch 14. Then, immediately contact is established between switch arm 66 and either contact 90 or 92, whichever may happen to lie in that direction, changeover switch 14 will function causing contact wiper 114 to bridge over from stationary contact 108 to the other of contacts 102 and 106 and the rearward headlamp, relatively speaking as before, will light. Further movement of the switch arm 66 in the same direction will cut off the direct current from the circuit and immediately thereafter impress through the adjacent branch of the rheostat the alternating voltage upon the system. Except for the brief instant while passing from the direct current contact 90 or 92, to its corresponding rheostat branch, the headlamp will remain lighted. Still further movement of the switch arm 66 along said rheostat branch will impress more and more voltage upon the driving motor and headlamp circuit. The ballast lamp 110 limits the current to the headlamp, while as soon as a sufficiently high torque is developed in the motor the locomotive will start. The speed of the locomotive is now controlled in the ordinary fashion by varying the position of switch arm 66 upon the rheostat branch. If now, however, switch arm 66 is returned from the rheostat branch to its adjacent direct current contact 90 or 92, the locomotive will stop but the headlamp will remain lighted. Returning switch arm 66 to the neutral position will extinguish that headlamp and movement of switch arm 66 through the neutral position will serve to reverse the motor and headlamp connections, first light the other headlamp with the locomotive at rest, and finally to start the locomotive in the opposite direction with that headlamp lighted.

The disclosed invention has therefore provided a system for toy locomotive headlamp control which will admit of either headlamp being lighted with the locomotive at rest or with the forward headlamp lighted with the locomotive in motion, entirely at the will, choice, and remote control of the operator. It has further provided a means to maintain a practically even brilliancy of the

lighted headlamp throughout the full range of conditions encountered.

It is not intended that the disclosed system of toy locomotive headlamp control and current supply be limited to application to the particular system of locomotive reversing control shown herein, nor are the system and devices shown and described herein to be limited to the exact forms and constructions described and illustrated, but the invention may be embodied in other forms and arrangements within the meaning of the language of the claims hereof.

Having thus described and illustrated my invention, what I claim is:

1. A toy electric locomotive having an electric motor and an electric headlamp, a power circuit for supplying current to the motor and to the headlamp when the motor is in operation, a supplementary circuit for supplying current to the headlamp when the motor is stationary, and a remotely operated controlling device for both circuits.

2. A toy electric locomotive having an electric motor and a headlamp, motor and lamp circuits in parallel, means under the control of the operator for supplying current to the circuits in sufficient amount to operate the motor and the headlamp and at the will of the operator in insufficient amount to operate the motor but sufficient amount to operate the lamp, and devices in the headlamp circuit for automatically increasing the resistance in such circuit when current is supplied to operate the motor.

3. A reversible toy locomotive having electric headlamps at each end, a lighting circuit for supplying current to the headlamps, an electrically operated switch for connecting one headlamp or the other into the lighting circuit, a controlling device remote from the locomotive for selectively actuating the headlamp changeover switch, a source of direct current for operating said changeover switch and lighting one headlamp or the other when the locomotive is at rest, another source of current for driving the locomotive and lighting one or the other headlamp throughout the speed range of the locomotive.

4. A reversible toy locomotive having an electric motor and electric headlamps at each end, a power circuit for supplying current to the motor and to one of the headlamps when the motor is in operation, an electrically operated switch for controlling the direction of rotation of the motor and for connecting one or the other of the headlamps into the power circuit, a supplementary circuit for actuating the switch and for supplying current to a headlamp when the motor is stationary, and a remotely operated controlling device for both circuits.

5. The method of operating a reversible toy electric locomotive having headlamps at

each end, which consists in supplying current to one or the other of the headlamps from the power circuit when the locomotive is in operation, and in controlling the direction of movement of the locomotive by means of a supplementary circuit which also supplies current to one of the headlamps when the locomotive is stationary.

6. The method of operating a reversible toy electric locomotive having headlamps at each end, which consists in supplying alternating current to the motor to drive the locomotive and to one of the headlamps when the locomotive is in operation, and in supplying direct current to operate one of the headlamps when the locomotive is stationary.

7. The method of operating a reversible toy electric locomotive which consists in supplying alternating current to drive the locomotive and to operate one of the headlamps when the locomotive is in operation, and in supplying direct current to control the direction of movement of the locomotive and to light one of the headlamps when the locomotive is stationary.

8. The method of operating a toy electric locomotive having an electric motor and an electric headlamp which consists in supplying current in sufficient amount to operate the motor and the headlamp, and supplying current in insufficient amount to operate the motor but sufficient to operate the lamp, and utilizing the heating effect of the current external to the lamp to increase the resistance in the headlamp circuit when sufficient current is supplied to operate the motor.

In testimony whereof I have hereto signed my name to this specification.

HARRY E. MORTON.
